GARMENT POCKET

Carl T. Habegger, Berne, Ind., assignor to Berne
Manufacturing Company, Berne, Ind., a cor-
poration of Indiana

Application October 7, 1936, Serial No. 104,522

2 Claims. (Cl. 2—247)

The present invention relates to a combination pocket structure and more especially to improvements in garment pockets and fastening means for closing the mouths of the pockets.

5 An important feature of the invention is to provide a garment such as an overall and the like, with a combination pocket which is attached to the front of the bib or apron of the overall and constructed so as to provide a main 10 pocket, an auxiliary pocket substantially coextensive in length and depth with the main pocket and a side pocket, said auxiliary pocket and said side pocket having their mouths located on the outside layer or wall of the auxiliary pocket to 15 permit convenient access thereto.

A further object consists in providing the auxiliary pocket with a sectional front layer or wall, in which the opposed vertical sides of the sections are separated to form a mouth for the 20 auxiliary pocket, and associating with the mouth a slide fastener for opening and closing the same. The slide fastener when moved to its closed position constituting an effective seal for the mouth to prevent the entrance of foreign matter into 25 the auxiliary pocket and also providing means which precludes the accidental opening of the mouth when the slide is moved to its closed position.

Another object consists in associating with one 30 side of the auxiliary pocket a side pocket, and providing the front layer of the auxiliary pocket with a scabbard pocket located to one side of the mouth of the auxiliary pocket and opposite to the side pocket.

35 A still further object comprehends the provision of a combination pocket for overall bibs, having the front layer or wall thereof preferably made of three sections of the same material as the bib, one of the end sections and the intermediate section having their opposed marginal edges separated from each other to provide a mouth closed by a slideable fastener, and the other end section having its marginal inner edge overlapping the adjacent inner edge of the intermediate section and secured thereto by a line of vertical stitching which is interrupted between its ends to constitute an opening or mouth for a side pocket, said side pocket being formed by the outer section and a lining located between 45 the intermediate layer and the outer layer of the pocket structure.

Other objects and advantages of the invention will become apparent from the following description when taken in conjunction with the accompanying claims and drawing.

Referring to the drawing, in which is illustrated a preferred embodiment of the invention:

Figure 1 is a front view of the bib of an overall showing my improved combination pocket secured thereto;

Figure 2 is an enlarged sectional view taken substantially along the line 2—2 of Figure 1;

Figure 3 is an enlarged sectional view taken substantially along the line 3—3 of Figure 1;

Figure 4 is a sectional view taken substantially 10 along the lines 4—4 of Figure 1;

Figure 5 is a sectional view taken substantially along the line 5—5 of Figure 1; and

Figure 6 is a sectional view taken substantially 15 along the line 6—6 of Figure 1.

Referring to the drawing in which like numerals indicate like parts in the several figures, 20 10 designates the bib of an overall to which is secured my improved pocket structure. As shown, the combination pocket is formed with 25 a front sectional layer or wall 11 which has its marginal edges 12 folded inwardly to receive the adjacent marginal portions 13 of the intermediate layer or partition 14 (Figure 2). The front face 15 of the bib 10 coacts with the intermediate 25 layer 14 to provide the main pocket 16. The upper edge of the front layer 11 is secured to the inner layer 14, preferably by a double line of stitching 17 (Figure 1) while the marginal sides and lower edges of the outer layer and intermediate layer may be attached to the bib by the 30 double row of stitching 18, which also extends inwardly and transversely at the upper ends of the outer layer and intermediate layer so as to secure the end portions of these layers to the bib 35 as at 19. The stitching 19 is interrupted medially of the width of the main pocket 16 to provide a mouth or opening 20 therefor. The front layer 11 may be made of the same material as the bib and preferably is composed of a central or intermediate section 21 and the end sections 22 and 23 (Figure 1).

The marginal side edge of the central section 21 adjacent the end section 23 has stitched thereto, a lining 24 which at its outer marginal edge, is connected to the bib by the stitching 18.

The intermediate layer 14 coacts with the sections 21 and 22 of the outer layer and the lining 24 to provide an auxiliary pocket 25 which preferably is coextensive in length and depth with the main pocket 16. The opposed vertical edges of the sections 21 and 22 of the front layer are spaced to constitute the mouth 26 for the auxiliary pocket 25 which is preferably closed by a slide fastener 27. The fastener 27 comprises a 55

pair of coacting interlocking members 28 and 29 (Figure 2) carried by the strips 30 and 31 respectively, which are secured to the inner sides of the sections 21 and 22 adjacent the mouth 26 by the stitching 32. A movable slide 33 having an operating handle 34 (Figure 1), is operatively associated with the interlocking members 28 and 29 so that when the slide is moved downwardly to the position as shown in Figure 1, it will cause the interlocking members to engage and provide a closure for the mouth of the auxiliary pocket 25. Conversely, when the slide 33 is moved upwardly, it will cause disengagement of the members 28 and 29 so as to open the mouth 26 and permit convenient access to the auxiliary pocket 25. The section 22 of the outer layer is provided with spaced transverse openings 35 and 36 which constitute a scabbard pocket between the section 21 and the intermediate layer 16 for receiving a pencil or the like 42. It will be seen that the scabbard pocket is formed adjacent the outer marginal edge of the section 22 and is spaced from the interlocking members 28 and 29 so as not to interfere with the auxiliary pocket 25 or obstruct access thereto through the mouth 26.

The lining 24 coacts with the outer section 23 to constitute a side pocket 37 (Figure 2). The inner marginal edge of the section 23 overlaps the adjacent edge of the section 21 and is secured thereto by the vertical row of stitching 38 which is interrupted to provide the opening 39 for permitting access to the side pocket 37. The mouth 20 of the main pocket may be closed by a snap fastener 40 carried by the central section 21 and arranged detachably to engage a complementary fixed member 41 secured to the inner layer 15.

The transverse interrupted row of stitching 19 provides a restrictive opening 20 for the main pocket 16, while the slide fastener 27 constitutes a closure for the mouth of the auxiliary pocket 25. It will be seen that when the fastener 27 is moved to its closed position, it will preclude the entrance of dirt or other foreign matter into the auxiliary pocket. Further the fastener will be retained in either its opened or closed position until manually actuated, thus precluding the accidental opening of the mouth 26 when the parts are in their closed positions. As the main pocket 16 and auxiliary pocket 25 are substantially the same length and depth, these pockets may be used for conveniently carrying articles of various sizes and shapes, while the auxiliary pocket 25 may be utilized to carry such articles as are to be kept clean or which it is desired to be carried without danger of acciden-

tally falling out of the pocket when the wearer of the overall assumes a bent-over posture.

While I have shown my improved pocket secured to the bib of an overall, it will be manifest that the same may be associated with various other types of garments. It is also to be understood that the form of the invention shown and described is merely illustrative of a preferred embodiment and that such changes may be made thereto as fall within the purview of one skilled in the art without departing from the spirit of the invention and the scope of the appended claims.

I claim:—

1. A combination pocket for garments including an inner layer formed from the garment, an intermediate layer, and an outer sectional layer, means securing the marginal edges of the intermediate layer to the outer layer, stitching securing the opposite sides and lower end of the intermediate layer and the outer layer to the inner layer to provide a main pocket between the garment and the intermediate layer, said stitching securing the upper ends of the outer layer and the intermediate layer to the inner layer and interrupted between the upper ends of the main pocket to provide a mouth for the latter, said outer layer and intermediate layer coacting to form an auxiliary pocket, said outer layer including end sections and a central section, one of the end sections being separated from the central section to provide an opening for the auxiliary pocket, a slidable closure for said opening, the other end section having its inner marginal edge overlapping the adjacent edge of the central section, a lining between the intermediate layer and the outer layer and coacting with the outer layer to provide a side pocket, and stitching securing the overlapped portions of the central section and the end section, said stitching being interrupted between its ends to provide a mouth for the side pocket.

2. In combination with a garment of the class described, a combination pocket including a main pocket and an auxiliary pocket secured to said garment, said auxiliary pocket being coextensive in length and depth with said main pocket, the front wall of the auxiliary pocket being formed of spaced sections to constitute a mouth therefor, a slidable fastener connected to the opposed edges of said sections to provide a closure for said mouth, and a lining interposed between the auxiliary pocket and one of said sections to provide a side pocket, said last-mentioned section being provided with a vertical opening to permit access to the side pocket.

CARL T. HABEGGER.
